(57) CLAIM

(21) Appl. No.: **29/178,137**

The ornamental design for a base for miter saw, as shown and described.

(22) Filed: **Mar. 21, 2003**

DESCRIPTION

(30) **Foreign Application Priority Data**

Sep. 25, 2002 (CN) 02 3 34350

FIG. 1 is a front view of the base for miter saw, which is the object of the present design;

(51) LOC (7) Cl. **15-09**

FIG. 2 is a rear view thereof;

(52) U.S. Cl. **D15/133**

FIG. 3 is a right side view thereof;

(58) Field of Search D15/133; 83/468.5,
83/438, 468.3, 471.1-471.3, 477, 581

FIG. 4 is a left side view thereof;

(56) **References Cited**

FIG. 5 is a bottom view thereof;

U.S. PATENT DOCUMENTS

FIG. 6 is a top view thereof; and,

6,595,095 B2 * 7/2003 Chen 83/473

FIG. 7 is a perspective view thereof.
